UNITED STATES PATENT OFFICE.

GEORGE H. DEIN, OF BROOKLYN MANOR, NEW YORK, ASSIGNOR OF ONE-HALF TO CHARLES BERG, OF NEW YORK, N. Y.

CURRENT COLLECTOR AND GUIDE.

Application filed May 27, 1922. Serial No. 564,085.

To all whom it may concern:

Be it known that I, GEORGE H. DEIN, a citizen of the United States, residing at Brooklyn Manor, county of Queens, and 5 State of New York, have made a certain new and useful Invention in Current Collectors and Guides, of which the following is a specification.

This invention relates to improvements in 10 current collectors and in collector guides which are particularly adapted for use in railless trolley systems.

The objects of my invention include the 15 provision of collectors and guides which are simple in construction, efficient in operation and whereby the cars may be economically operated and the feeder service constantly maintained.

A further object includes a construction 20 which admits of great flexibility and which maintains uniform and constant contact under extreme circumstances, permitting even a complete turn of the bus without removing the trolley.

25 A still further object includes the provision of a protective guard for maintaining proper contact; and a still further object includes the provision of a simple and efficient guide and cross-over.

30 Other objects will appear hereinafter, and I maintain these objects by the construction illustrated in the accompanying drawing and defined in the appended claims.

In the drawing:

35 Figure 1 is a plan view of my collector device.

Fig. 2 is a side view thereof.

Fig. 3 is a side view at right angles to 40 Fig. 2.

Fig. 4 is an enlarged sectional view of a portion of my collector, taken on lines 4-4 of Fig. 1.

Fig. 5 is a view of a modification, shown in part.

45 Fig. 6 is a plan view of a cross-over guide and frame.

Fig. 7 is an elevation showing a wire supporting spacing frame.

Fig. 8 is an enlarged detail view of a part of Fig. 7. 50

Fig. 9 is a view taken on lines 9-9 of Fig. 7, looking in the direction of the arrows.

Fig. 10 is a view taken on lines 10-10 of Fig. 6.

Referring to the drawing wherein like 55 numerals designate similar parts, a collector 11, preferably disk-shaped, is carried on the upper end of a trolley pole 12, by suitable supporting fixture 13, which is pivotally connected to a supporting connection 14 on 60 the collector.

The collector disk or plate 11 comprises 65 two conductor segments 15 and 16 which are firmly supported in any suitable manner, as on an insulation disk 17, with an extended portion 18 electrically separating segments 15 and 16 as is well understood. The conductor segments and exposed part of disk 17 are provided with an offset 19 and an adjacent extension or flange 20 for 70 guiding the conductor feed and return wires 21 and 22. Flange 20 terminates in a tapering portion 23 for ready pick-up and guiding of the conductor wires. This construction is shown in its simplest form in Fig. 5. 75

To further guide, protect or clean the conductor wires I provide special flappers or wings 24 and 25, which in a preferred form are connected to segments 15 and 16 in any suitable or desired manner, as by hinges 26 80 and 27. Spring members 28 which are fastened to the collector disk by bolts 29 and 30, or their equivalents, pass through a slot 31 in the supporting fixture 13 for steady-

85 ing and positioning the collector by engagement with the fixture 13 in slot 31 as is shown, for example, by Figs. 2 and 3. A suitable guide rope 32 may be attached to the pole fixture and cooperating with this

90 rope are the flapper cords 33 operating over a projection 34 and secured to the flappers at 35 for raising said flapper wings when the collector is to be brought into contact with the conductor wires, or when, as may

95 happen under rare circumstances, the trolley has been displaced.

The raised position of the flapper wing is indicated by dotted lines, in Fig. 3, and any suitable means, as springs 36, may be provided to hold said flapper wings in place. 5 It is understood that the usual conductor wires (not shown) pass from the collector segments through the fixture and pole to the motor for supplying the current in the manner common for this type of motor. It 10 is also apparent, from the disclosure thus far given, that the construction of my collector permits unusual and most effective following of the conductor wires and at the same time permits an exceptional range in 15 motion and movement of the bus. It is further apparent that the flappers, besides serving as a guide, provide means also for removing sleet and ice from the wires, and to most effectively use the same, special sup- 20 porting guides and cross-overs have been provided.

The cross-over and guide construction herein disclosed is illustrative merely and the cross-over comprises a rectangular frame 25 40 having cross bars 41 which support, by means of suitable insulators 42, the corner guide plate 43. This plate carries wire clamps 44 for clamping and holding the conductor wires 21 or 22, as is readily under- 30 stood from an inspection of Fig. 6.

In order to properly space and support the conductor wires I provide a standard cross-over 45 having depending members 45 for engaging insulators 46. In these insula- 35 tors are held the boot-shaped L-members 47 which are provided with toe extensions 48, and clamp members 49 for holding the con- 40 ductor wires 21. The cross-overs and cross- over frame may further be provided with 45 eyes 50 for supporting guy wires.

The invention and construction herein disclosed, while primarily designed for trackless trolley busses or cars, are obviously adapted for operation of trolley sys- 45 tems employing tracks, and while I have disclosed a specific embodiment of my in- 50 vention, I do not thereby desire to be under- stood as having thus limited myself unduly. What I claim, therefore, as new and use- 55 ful, of my own invention, and desire to se- cure by Letters Patent is:

1. In current collectors and guides for trolley systems, a collector member comprising an insulator disk, and conductor 55 segments arranged diametrically opposite each other on said disk.

2. In current collectors and guides for trolley systems, a collector member comprising an insulator disk, conductor seg- 60 ments insulated from each other and car- 65 ried on said disk, and a flange encompassing said disk for guiding the conductor wires of said systems.

3. In current collectors and guides for trolley systems, a collector member com-

prising an insulator disk, conductor seg- 70 ments arranged diametrically opposite each other on said disk, and means for guiding the current supply wires.

4. In current collectors and guides for trolley systems, a collector member comprising an insulator disk, conductor segments arranged diametrically opposite each other on said disk, and movable guides for main- 75 taining the current supply wires in contact- 80 ing position.

5. In current collectors and guides for trolley systems, a collector member comprising an insulator disk, conductor segments arranged diametrically opposite each other 85 on said disks, said segments being each pro- 90 vided with an offset, means for guiding the current supply wires in said offset, said means comprising flapper wings and tensioning mem- bers.

6. In current collectors and guides for trolley systems, a collector member comprising an insulator disk, conductor segments arranged diametrically opposite each other on said disks, means for guiding the current 90 supply wires, said means comprising flapper wings and tensioning members, and means for at-will moving said wings.

7. In current collectors and guides for trolley systems, a collector member comprising an insulator disk, conductor segments arranged diametrically opposite each other on said disk for engaging the feed wires of 100 said system, and means for supporting said feed wires in contacting relation to said collector member.

8. In current collectors and guides for trolley systems, a collector member comprising an insulator disk, conductor segments arranged diametrically opposite each other on said disk for engaging the feed wires of 105 said system, and means for gripping and holding said wires in contacting relation with said collector member.

9. In current collectors and guides for trolley systems, a collector member comprising an insulator disk, conductor segments arranged diametrically opposite each other on said disk, and means for positioning said collector member.

10. In current collectors and guides for trolley systems, a collector member comprising an insulator disk, conductor segments arranged diametrically opposite each other on said disk, and elastic members for guid- 110 ing said collector member.

11. In current collectors for trolley buses operating feed and return wires, a support- 115 ing fixture carried on the end of a trolley pole, said fixture being provided with a slot at right angles to the position of the pole, a disk collector mounted on said fixture, and guides on said collector passing through said slot for maintaining said disk in a hor- 120 125 130 izontal position.

12. In current collectors for trolley buses operating feed and return wires, a trolley pole, a supporting fixture mounted on said pole, said fixture being provided with a slot, 5 guide springs passing through said slot, a disk collector pivotally mounted on said fixture and having said springs attached at points opposite said pivotal mounting for

maintaining said disk collector in contact with said wires, whereby the trolley bus 10 may be completely turned around without dislocating the disk collector.

In testimony whereof I have hereunto set my hand on this 23rd day of May A. D., 1922.

GEORGE H. DEIN.
